SWIMMING POOL ENCLOSURE

John P. Kwake, 2507 Carob Drive, Los Angeles, Calif.

Filed Mar. 8, 1965, Ser. No. 34,140

Term of patent 14 years

(Cl. D13—1)

FIGURE 1 is a perspective view of my swimming pool enclosure showing the novel design therefore;

FIGURE 2 is a top plan view thereof; and

FIGURE 3 is an end elevation view thereof, as seen from the left of FIGURE 1.

The dotted line showing in FIGURE 1 is for illustrative purposes only.

I claim:

The ornamental design for a swimming pool enclosure, substantially as shown and described.
